UNITED STATES PATENT OFFICE.

ALEXANDER SIMONET, OF HOMESTEAD, PENNSYLVANIA.

REVERSING VALVE.

Application filed July 24, 1925. Serial No. 45,849.

My invention relates to reversing valves, that is, to valves for reversing the flow of gaseous fluid through a system.

My invention is primarily adapted for use 5 of producer-gas in conjunction with open-hearth furnaces, wherein the gas is directed through the fire-room (hearth) first in one direction and then in another, or the gas is directed alternately through a pair of heating chambers. However, my invention is 10 not to be limited to such specific use but may be adapted for other purposes wherein it is desired that the intake and exhaust gases may be controlled and reversed by a single 15 valve. While the invention may be used for various purposes, I have illustrated and will describe the same as used in conjunction with a reversing blast furnace and particularly wherein a fuel gas is employed for the blast 20 instead of air only.

The object of my invention is to provide an improved valve of the class mentioned wherein the blast gas may be directed through the system first in one direction and 25 then in another and wherein the exhaust gas may be directed from either of two exhaust channels to a single flue or chimney. A further object of my invention is to provide a device as mentioned so constructed that the 30 incoming fluid gas will be automatically shut off during the reversing operation. A further object of my invention is to provide a device as mentioned which shall be of comparatively simple construction and easy to 35 operate and one which will not readily get out of order. Other objects will appear hereinafter.

With these objects in view my invention consists generally in upper and lower casing 40 elements and a bell arranged between the same with water sealed joints between the bell and the upper and lower casing elements, conduits leading from the lower casing element and partitions in the bell maintaining a separation between the fuel and 45 exhaust gases and for directing said gases to the desired channels. My invention further consists in a device as mentioned in combination with means for raising and lowering the bell and for turning the same after elevation. My invention further consists 50 in a device as mentioned of such construction as to automatically shut off the flow of fuel gas to the bell when the latter is raised for turning, and reversing the flow of gases. 55 My invention further consists in various de-

tails of construction and arrangements of parts all as will be fully described herein-after and particularly pointed out in the claims.

My invention will be more readily understood by reference to the accompanying drawings forming a part of this specification and in which—

Fig. 1 is a vertical section of the device 65 on substantially the line 1—1 of Fig. 2,

Fig. 2 is a horizontal section on the line 2—2 of Fig. 1,

Fig. 3 is a horizontal section on the line 3—3 of Fig. 1,

Fig. 4 is a vertical section of the bell on the line 4—4 of Fig. 3,

Fig. 5 is a bottom plan view of the bell,

Fig. 6 is a diagram illustrating the arrangements and use of the valve in conjunction with a reversing blast furnace, and

Fig. 7 is a detail section on the line 7—7 of Fig. 5.

Referring now to the drawings 1 indicates the base or bottom elements of the casing which comprises outer and inner concentric channels 2 and 3 respectively connected by three radial channels 4, 5 and 6, forming openings or ports 7, 8 and 9 in the bottom of the device, which communicate with ducts or conduits 10, 11 and 12, leading respectively to a chimney 13, and to heating chambers 14 and 15, as indicated in Figs. 2 and 6. The chambers 14 and 15 are connected to the blast furnace 16 by blast ducts 17 and 18 and also by exhaust gas ducts 19 and 20. The mouths of these ducts 17, 18, 19 and 20, where they enter the chambers 14 and 15 are controlled by suitable dampers 21 and 22 so that the blast duct of one chamber is open when the exhaust to the other is open and vice versa.

The top element of the casing comprises a gas chamber formed of inner and outer concentric cylindrical walls 23 and 24 respectively connected at their upper ends by an annular plate 25 constituting the top of the chamber. This is supported in any suitable way, as by a frame-work 26, which is illustrated diagrammatically only in Fig. 1. 27 indicates the gas inlet connected with any suitable source of supply. Between the upper and lower casing elements is a bell 28 comprising inner and outer cylindrical walls 29 and 30 and a top plate or closure 31. The lower edges of the walls 29 and 30 rest within the annular channels 2 and 3 of

the bottom elements, which channels, together with the radial channels 4, 5 and 6, are filled with water to form a gas seal. The top of the bell 28 is provided with inner and outer concentric channels 32 and 33 respectively, which receive the lower edges of the walls 23 and 24 of the top casing element or gas chamber. These channels are filled with water to form a seal between the 10 gas chamber and the bell. Arranged within the bell 28 are radially disposed vertical partitions 34, the lower edges of which terminate short of the bottom of the walls 29 and 30, but normally extend into the radial 15 channels 4, 5 and 6, dividing the bell into a blast gas compartment 35 and a waste gas compartment 36. These partitions are preferably double walled as illustrated so as to contain water for cooling the same. The 20 top of the bell 28 is provided with a gas inlet port 37, about which is arranged a short vertically extending pipe 38. The length of the pipe 38 is such that its upper end will closely contact the top 25 of the 25 gas chamber when the bell is raised sufficiently to permit the lower edges of the partitions 34 to pass over the walls of the channels 4, 5 and 6 for a purpose hereinafter described.

30 A fixed shaft 39 is provided which constitutes a guide for the bell 28, a pair of bearings 40 being fixedly arranged within the cylindrical element 29 of the bell. Fixed to the upper bearing member 40 is an upwardly extending sleeve 41 upon which is formed an annular flange 42. 43 indicates a sleeve arranged about the sleeve 41 and provided with racks 44, meshing with pinions 45. The sleeve 41 is rotatable within the sleeve 43, whereas the latter is preferably non-rotatable. The upper end of the sleeve 43 is provided with a flange 46 between which and the flange 42 are ball-bearings 47. It is obvious that by turning the pinions 45, the bell 28 may be raised or lowered as desired. The sleeve 41 extends above the flange 42 and slidably mounted upon the upper end thereof is a pinion 48 meshing with a gear 49 adapted to be driven in any suitable manner. By means of the pinion and gear 48 and 49, the bell may be rotated. The bell is counterweighted as shown to facilitate the operation of the device. 25' indicates the counterweights which may be connected to the bell in any desired manner.

60 The operation of the device is as follows: The bell 28 normally rests in a position indicated in Fig. 1 with the lower edges of its walls 29 and 30 resting in the bottoms of the channels 2 and 3 and the lower edges of the partitions 34 submerged in the water of the radial channels as illustrated. Fluid 65 gas under pressure is passed through 27 to the gas chamber from which it passes through the pipe 38 to the chamber 35 of the bell 28. As illustrated in the drawings, this is in communication with the passageway 11 leading to a heating chamber 14 and thence through the blast duct 17 to the furnace 16. The waste gas returns through the duct 20 to the heating chamber 15, where it heats the latter to a high temperature, and passes through the duct 12, and the port 9, to chamber 36 of the bell, and 75 out through the port 7 to the chimney duct 10. After the chamber 15 is sufficiently heated, the bell 28 is raised by means of the mechanism above described and then turned approximately 120° until its walls 34 are above the channels 5 and 6, and then lowered. It will be noted that this will reverse the flow of gas through the heating chambers and furnace, as the blast gas will now pass through the port 9 to the duct 12, thence through the chamber 15, where the gas is heated and then through the blast duct 18 to the furnace 16. It is to be understood that when the bell is shifted the dampers 21 and 22 are also operated to close the ducts which were formerly open and to open those formerly closed. The waste gas passes out through the duct 19 to the heating chamber 14, which it heats to a high 80 temperature and then passes out through the duct 11 to the port 8 into the chamber 36 of the bell and through the port 7 to the chimney duct 10. When the bell 28 is raised the end of the pipe 38 engages the top 25 of the gas chamber and automatically cuts off the flow of gas to the bell while the latter is being turned. When the chamber 14 is sufficiently heated, the valve is again reversed, as are also the dampers 21 and 22, 85 and the operation repeated.

90 I claim:

1. A device of the class described comprising a base element having a plurality of ports, and an upper gas chamber in combination with a bell arranged between said base and said gas chamber and provided with partitions adapted to control said ports and means for shifting said bell to effect communication between said gas chamber and one of said ports and communication between others of said ports, and means on said bell adapted to co-operate with a portion of said gas chamber to automatically cut off the gas when the bell is raised, substantially as described.

100 110 115 120 125 130

2. A device as set forth in claim 1 in combination with water sealed joints between said bell and said gas chamber and similar joints between said bell and base element, substantially as described.

3. A device of the class described comprising a base element consisting of concentric annular channels and three radial channels connecting the same, a bell having inner and outer cylindrical walls with their

lower edges arranged in said annular channels and provided with a pair of partitions having the lower edges arranged in two of said radial channels, there being liquid in 5 said channels to form a seal, a gas chamber above said bell, said bell being provided with an annular water filled channel receiving the lower end of the chamber walls, means for admitting gas to said gas 10 chamber, a communicating port between said gas chamber and said bell, the inner cylindrical wall of said bell forming a central chamber open to the atmosphere and means in said central chamber for raising, 15 lowering and turning said valve, substantially as described.

4. A device of the class described comprising a base element having a plurality of ports and an upper gas chamber in combination with a bell arranged between said base and said gas chamber and provided 20 with partitions adapted to control said ports, means for raising, shifting and lowering said bell to effect communication between said gas chamber and one of said ports and communication between others of 25 said ports, said gas chamber having a flat top, and said bell being provided with a gas inlet port in its top, and a vertical pipe 30 communicating with said port and adapted when the bell is raised to engage the flat

top of the gas chamber to automatically close communication with said port, substantially as described.

5. A device of the class described comprising a base element consisting of concentric annular channels and radial channels connecting the same, a bell having inner and outer cylindrical walls with their lower edges arranged in said cylindrical 35 channels and provided with partitions dividing the bell into chambers and having the outer ends of said partitions arranged in certain of said radial channels, there being liquid in said channels to form a seal, 40 a gas chamber above said bell, said bell being provided in its top with a gas inlet port communicating with one of the chambers of said bell, a pipe surrounding said port and projecting upwardly and means on said chamber for engaging and closing the upper 45 end of said pipe when the bell is raised sufficiently to withdraw the radial partitions from their respective channels, substantially as described.

6. A device as set forth in claim 1 in combination with means for counter-balancing the bell, substantially as described.

In testimony whereof I have signed my name to this specification.

ALEXANDER SIMONET.
